UNITED STATES PATENT OFFICE.

SAMUEL H. MILLER, OF LA JUNTA, COLORADO.

LATCH.

1,351,300.

Specification of Letters Patent. Patented Aug. 31, 1920.

Application filed December 13, 1919. Serial No. 344,578.

To all whom it may concern:

Be it known that I, SAMUEL H. MILLER, a citizen of the United States, residing at La Junta, in the county of Otero and State of Colorado, have invented certain new and useful Improvements in Latches, of which the following is a specification, reference being had to the accompanying drawings.

This invention relates to certain improvements in latches, and has relation more particularly to a device of this general character embodying a latch bolt supported substantially for rectilinear movement, and it is an object of the invention to provide novel and improved means whereby the latch may be effectively held in a retracted position to avoid the necessity of operating the spindle of the lock.

It is also an object of the invention to provide novel and improved means for maintaining the latch bolt in retracted position, and which means is operated exteriorly of the casing or of the door to which the lock may be applied.

The invention consists in the details of construction and in the combination and arrangement of the several parts of my improved latch whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view partly in section and partly in elevation illustrating a latch constructed in accordance with an embodiment of my invention;

Fig. 2 is a view similar to Fig. 1, showing certain of the parts in a second position, and,

Fig. 3 is a fragmentary view in perspective illustrating the tensioning means carried by the vertically disposed arm or member, as herein included.

As disclosed in the accompanying drawings, C denotes a lock casing adapted to be applied to a door in a conventional manner and mounted for substantially rectilinear movement within said casing is a latch bolt L of a well known type, and which latch bolt L is adapted to be operated through

the instrumentality of a spindle, as is also well known.

Mounted within the casing C at a point below the latch bolt L and for movement in a vertical direction is an elongated member or arm 1. The lower end portion of the member or arm 1 is pivotally engaged, as at 2, to the free end portion of a lug or extension 3 carried by the central portion of a vertically disposed bar 4. In pivotal engagement, as at 5, with each end portion of the member 4 is a shank or stud 6, constituting a clutch member, and which shank is slidably disposed through the front face of the casing C.

When the shank or stud 6 is forced inwardly, the member 4 is rocked upwardly about its pivotal connection 5 with the upper shank or stud 6, resulting in an upward movement of the member or arm 1. When the latch bolt L is retracted the upper end portion of the member or arm 1 engages within a recess or notch 7 produced in the lower face or edge of the bolt L, and where- by said bolt is maintained retracted so that the door to which the lock is applied may be readily opened without the necessity of turning the spindle, or manipulating other operating mechanism for the bolt L. This is particularly desirable in connection with a door for a store, so that persons having packages or the like in their hands do not have to retract the bolt L when they desire to open the door.

With the bolt L held in a retracted position through the instrumentality of the member or arm 1, and if it is desired to return the bolt L to its normal or active position, it is only necessary to force the upper shank or stud 6 inwardly, and which movement results in a downward movement of the member or arm 1 sufficient to release the bolt L. This movement also results in the lower shank or stud 6 being forced outwardly sufficient to permit its operation to again engage the member or arm 1 with the latch L. It is also to be understood that when the lower shank or stud 6 is forced inwardly the upper shank or stud 6 is forced outwardly a distance sufficient to permit its operation to disengage the arm or member 1 from the latch L.

The shanks or studs 6 have movement through the openings 8, produced in the front face of the casing C, and the outer ends of said openings 8 are enlarged, as at 9,

- to facilitate the requisite manipulation of the shanks or studs 6, so that when either of said shanks or studs 6 extended outwardly of the casing, they will offer no obstruction or hindrance to the closing of the door, as the outer end portion of said shank or stud 6 will be substantially flush with or slightly inwardly of the outer face of the front of the casing C.
- 10 The upper portion of the member or arm 1 is positioned between the inwardly directed lugs 9 carried by a side face of the casing C, and which lugs operate to maintain the member or arm 1 in desired position.
- 15 I also find it of advantage to provide a face of the member or arm 1 with a flat spring 10 or other tensioning device which coacts with the adjacent side face or wall of the casing C to firmly maintain the member or arm 1 against movement, and particularly against downward movement when said member or arm 1 is elevated to engage within the notch or recess 7 in the lower edge of the latch bolt L.
- 20 As is particularly illustrated in Fig. 3, the spring 10 comprises a leaf secured to the member but substantially midway the length of the spring. The spring 10 is disposed longitudinally on such curvature whereby the extremities or opposite end portions thereof have contact with a side face of the casing C.
- 25 As is particularly illustrated in Figs. 1 and 2 of the drawings, it is to be noted that the bar 4 is supported substantially midway its length, as at 12, for rocking movement.

From the foregoing description it is thought to be obvious that a latch constructed in accordance with my invention is par-

ticularly well adapted for use by reason of 40 the convenience and facility with which it may be assembled and operated, and it will also be obvious that my invention is susceptible of some change and modification without departing from the principles and spirit 45 thereof, and for this reason I do not wish to be understood as limiting myself to the precise arrangement and formation of the several parts herein shown in carrying out my invention in practice except as herein- 50 after claimed.

I claim:

In combination with a lock mechanism including a casing and a latch bolt, a pair of spaced studs having sliding movement 55 through a wall of a casing, a member pivotally engaged with and connecting the inserted end portions of the studs, and provided with an outstanding arm, a vertically disposed member pivotally engaged at one 60 end portion with the opposite end portion of said arm, said last-named member coacting with the bolt when retracted and upon inward movement of one of the studs for holding the bolt against outward movement, 65 a pair of spaced lugs carried by the casing adjacent the latch and between which the free end portion of the last named member is freely disposed, and a spring leaf secured substantially midway its length to the sec- 70 ond member, the extremities of said spring leaf coacting with the face of the casing for holding said second member against movement away from the bolt when in working engagement therewith.

In testimony whereof I hereunto affix my signature.

SAMUEL H. MILLER.
